UNITED STATES PATENT OFFICE.

WILLIAM L. FATTERSON, OF ROCHESTER, NEW YORK, ASSIGNOR TO BAUSCH & LOMB
OPTICAL COMPANY, OF ROCHESTER, NEW YORK.

CASE FOR HEMACYTOMETER AND SIMILAR APPARATUS.

Application filed May 12, 1923. Serial No. 638,636.

My present invention relates to containers or cases for hemacytometer and similar apparatus, the chief object being to provide a compact, sanitary and convenient container 5 or case for apparatus of the variety employed in preparing fluid specimens for microscopical analysis, such, for example, as the hemacytometer slide, cover plate and pipette commonly employed for making a 10 blood or other fluid analysis. To these and other ends, the invention resides in certain improvements and combinations of parts all as will be hereinafter more fully described, the novel features being pointed out in the 15 claims at the end of the specification.

In the drawings;

Fig. 1 is a plan view of a container or case embodying the present invention, with the case cover in open position.

20 Fig. 2 is a central, longitudinal sectional elevation of the case, with the cover closed, and with a slide and cover plates positioned therein.

Fig. 3 is a sectional elevation on line 25 3^a—3^a in Fig. 2.

Fig. 4 is an enlarged detail view of parts shown in Fig. 3.

Similar reference numerals throughout the several views indicate the same parts.

30 The present invention provides an improved case for apparatus for preparing fluid specimens for microscopical analysis, such, for example, as a hemacytometer slide, one or more cover plates therefor, and one 35 or more pipettes for supplying specimens to be tested, the case being preferably formed of sheet metal of a relatively non-corrodable character, such, as brass or aluminum lined with enamel or other suitable vitreous material, the advantages of which, from sanitary 40 aspects, as well as manufacturing economy will be obvious to those skilled in the art.

45 Referring more particularly to the drawings, the present embodiment, disclosed herein by way of illustration, preferably comprises a case including a body portion, 5, and cover, 6, each struck up from sheet metal in the form shown, and connected by hinge means as shown at 7. Secured to the 50 body portion, preferably adjacent the center of the latter, is a one piece sheet metal tray, 8, having substantially the same size and shape as a hemacytometer slide, indicated at 8^a, with its marginal edge portion 55 turned upwardly, as at 9, to retain the slide

thereon. Such upturned marginal portions, however, are preferably not continuous, but formed with intermediate spaces, as at 10, to facilitate gripping the slide, to lift the same from the tray. The latter preferably has a 60 portion of its surface depressed, as at 11, which portion is secured by welding, riveting, or other suitable means, to the case. This latter feature serves two purposes: it 65 not only supports the tray in elevated relation with the case to thereby increase the accessibility of the slide, but also provides at such depressed portions a receptacle for one or more slide cover plates indicated at 12, thus compactly carried beneath the slide. 70 Preferably also, the depressed portion is furnished with studs as at 13, to hold the cover plates in spaced relation therewith to facilitate gripping and removal.

75 Means are provided for retaining a slide and cover plates in position on the tray, as described, comprising preferably a strip 14, riveted adjacent center, to the case cover, with free resilient ends, 15, spaced from the latter for yielding engagement with the upper surface of the slide, when the cover is closed, to retain the slide and plates in position.

80 The location of the tray for the slide and cover plates adjacent the center of the case body portion, as shown, provides space for the arrangement of one or more pipettes within the case around the tray, and means are provided for holding pipettes in such 85 position, comprising spring clip means, indicated generally at 16, of which two are employed in the present instance, and located on the same side of the tray, although a different number of such clip means may, of course, be employed, differently arranged. 90 Each clip means preferably includes a pair of substantially U shaped strips 17 and 18 of resilient metal, located one within the other, respectively, as shown in Fig. 4, and riveted together and to the case. Each pair of adjacent arm terminals are preferably formed to extend in spaced relation, as at 19 and 20, to receive and retain the body portion of a pipette, the usual flexible tube portion of which may be arranged or coiled 95 in the case around the tray. Provision is thus made in the present instance for holding two such pipettes each of which is retained in position at its ends by the clip devices 16. The elevated tray serves to pro- 100 105 110

vide a channel-like space between itself and the marginal wall of the case body in which the pipette tubes are received and retained as described.

- 5 The case body and cover are provided with suitable latch means for holding the same in closed position, comprising in the present instance a spring latch plate 21, fixed at one end 22, to the marginal wall of the case body portion, and having its other end provided with an upstanding hook, 23, adapted to spring over a catch plate, 24, on the marginal wall of the cover. The latch has a finger piece, 25, projecting through a slot 10 in the casing for operating the latch to release the cover.

The construction of the case and its parts of sheet metal and the compact arrangement described substantially reduces the dimensions of the case to convenient pocket size. The employment of metal of a character resisting corrosion lined with enamel or other vitreous material affords a highly sanitary type of case, which may be readily sterilized 25 and cleaned without injury. Such construction, furthermore, materially reduces the cost of manufacture, and provides a convenient and attractive case for the purposes described.

20 I claim as my invention—

1. A case of the character described, comprising relatively movable body and cover sections, a tray within said body section comprising a dished portion secured to the body section and adapted to receive a slide cover plate, said portion having two of its sides extended in spaced and in substantially parallel relation to the casing wall upon which it is secured, said extensions being 25 adapted to receive a slide and means upon the cover section adapted when the latter is closed to engage and hold the slide upon said extensions.

2. A case of the character described, comprising relatively movable body and cover sections, a tray within said body section comprising a dished portion secured to the bottom of the body section and adapted to receive a slide cover plate, said portion having oppositely disposed extensions in spaced and substantially parallel relation to the

bottom of the body section, said extensions being adapted to receive a slide and each having upstanding guards for the slide and a resilient strip secured to the cover section 55 intermediate the ends of the latter and adapted to yieldingly engage the slide when said cover section is in closed position.

3. A case of the character described, comprising relatively movable body and cover sections, a tray having a dished portion for receiving a slide cover plate, said portion being secured to the bottom wall of the body section and having oppositely arranged extensions spaced from and substantially 60 parallel to said wall and adapted to support a slide above the slide cover plate and means supported by a cover adapted to engage the slide to hold it in position when the cover is closed.

4. A case of the character described, comprising relatively movable body and cover sections, a one piece tray having a central portion in the form of a receptacle adapted to receive a slide cover plate and being secured upon the bottom wall of the body section and having oppositely arranged extensions spaced from and substantially parallel to said wall and adapted to receive a slide and a spring clip secured to the cover 75 section and adapted to yieldingly engage the slide when the cover section is in closed position.

5. A case of the character described, comprising relatively movable body and cover sections, a tray having a central portion in the form of a receptacle secured to the bottom wall of the body section and provided with inwardly extending projections for receiving a slide cover plate and having oppositely arranged slide receiving extensions spaced from and parallel to said wall and projecting in spaced relation to all parts of the case, said extensions having up-turned 80 edge portions for retaining the slide, a spring clip secured to the upper section adapted to engage the slide when said upper section is in closed position and means on the body section at one side of said tray for holding a pipette.

WILLIAM L. PATTERSON.
